UNITED STATES PATENT OFFICE.

HENRY N. NOTTINGHAM, OF PORTER, OKLAHOMA.

CHAIR-BRACE.

1,287,084.

Specification of Letters Patent.

Patented Dec. 10, 1918.

Application filed February 23, 1918. Serial No. 218,774.

To all whom it may concern:

Be it known that I, HENRY N. NOTTINGHAM, a citizen of the United States, residing at Porter, in the county of Wagoner and State of Oklahoma, have invented certain new and useful Improvements in Chair-Braces, of which the following is a specification.

Chairs and kindred articles of furniture are subjected to severe strain, and as a result, the back and legs become loose and detached, and the period of service is comparatively short lived and frequent repairs are necessary in order to maintain the chair in serviceable and safe condition.

The present invention provides means whereby the legs, back and other parts of the chair may be connected in a manner to prevent their loosening and separating, thereby prolonging the period of service of the chair and obviating the cost incident to repairs.

The invention provides an attachment which may be cheaply constructed and which is light and of such formation as not to detract from the appearance of the chair when applied thereto, the device being of sectional formation so as to occupy a minimum amount of space when not in active position.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

In the drawings:

Fig. 1 is a plan view of a chair brace embodying the invention.

Fig. 2 is a sectional view on the line 2—2 of Fig. 1 looking in the direction of the arrows.

Fig. 3 is a detail view showing more clearly the joint between one of the attaching loops and the connecting member.

Corresponding and like parts are referred to in the following description and indicated in the several views of the drawings by like reference characters.

The brace comprises two attaching loops 1 and 2, and an intermediate connecting member 3. The several parts are preferably constructed of stout wire of a gage to with-

stand the strain. The member 2 is formed of a length of heavy wire doubled upon itself to form a loop having its terminal portions brought together and bent to provide eyes 4. The member 1 is similarly constructed of a single length of stout wire which is doubled upon itself to form a loop 5 and having its end portions crossed and the extremities of such end portions threaded for a short distance, as indicated at 6. 60 A comparatively short bar 7 has openings formed therein near its ends and at a central point, the end openings receiving the threaded ends 6 of the member 1. Nuts 8 are mounted upon the projecting threaded 70 ends 6 of the member 1 and engage the cross bar 7. The intermediate connecting member 3 consists of a length of stout wire having an eye 9 at one end which engages the eyes 4 of the member 2 and having its opposite end threaded for a short distance as indicated at 10 and passing through the central opening of the cross bar 7 and receiving the nut 11.

It will be understood that the brace involves a relatively light construction and withal is durable and capable of resisting strain, and when in position does not detract from the appearance of the chair or other article of furniture to which it is applied. The interengaging of the eyes 4 and 9 admits of the member 2 folding upon the member 3, and by reason of the member 3, passing through the central opening of the cross bar 7, the member 1 may be slid along 85 the member 3 so that the three members 1, 2, and 3 may occupy a superposed position, thereby reducing the length of the brace so as to occupy a minimum amount of space. By having the side elements of the member 90 1 crossed, the loop 5 may be of a minimum size and better adapted to engage the part to which it is connected.

It is well known that chairs and like articles of furniture are damaged by persons 100 rocking and tilting the same. This habit causes the back and legs to become loose and eventually to separate with the result that the chair becomes wobbly and unsafe for use. The present invention provides a 105 brace wherein the terminal loops 2 and 5 may receive legs of the chair or other parts to be connected, after which the nuts 6 and 11 are turned on the respective threaded parts so as to draw the loops 2 and 5 to 110

gether and hold the parts engaged thereby from separating, thereby preventing any possible looseness of the parts so coupled or connected.

5. What I claim is:

A chair brace comprising a length of wire formed into a loop and having its terminal portion brought together and bent to provide eyes, a second length of wire doubled upon itself to form a loop and having its end portions crossed and threaded for a short distance from their extremities, a cross bar having a middle and end openings, the latter receiving the threaded ends of the

second loop member, a connecting member 15 having an eye at one end engaging the eyes of the first mentioned loop member and having its opposite end threaded and passing through the central opening of the cross bar, and nuts mounted upon the threaded 20 ends of the several parts passing through the said cross bar.

In testimony whereof I affix my signature in presence of two witnesses.

HENRY N. NOTTINGHAM.
